UNITED STATES PATENT OFFICE.

ALPHONZO B. BOWERS, OF SAN FRANCISCO, CALIFORNIA.

DREDGING APPARATUS.

SPECIFICATION forming part of Letters Patent No. 364,158, dated May 31, 1887.

Original application filed December 9, 1876. Renewed April 16, 1879. Divided and this application filed February 26, 1887.
Serial No. 229,025. (No model.)

To all whom it may concern:

Be it known that I, ALPHONZO B. BOWERS, of San Francisco, California, civil engineer, have invented a novel Device for Dredging, 5 which is herein set forth, with details of construction, by reference to the accompanying drawings.

It is a sixth division of the application filed by me December 9, 1876, and renewed April 10, 1879, being portions thereof shown in Figures 10 and 17 of the original drawings.

It consists, mostly, in a hollow, and usually a rotary, shell mounted on suitable bearings and provided with excavating devices placed over 15 openings in said shell through which the spoil passes from said devices to the interior of the shell and to a pipe for removing the spoil; also, in arranging the openings and excavating devices spirally around the shell to make at least 20 one full cut across the whole face of the excavation at each revolution; also, in arranging the openings and excavating devices in reversed spirals around said shell to produce an even-balanced strain and avoid the rocking of 25 the hull caused by devices set in a single spiral from end to end of a long transverse cylinder, such as is sometimes used, and herein shown, for cutting the full width of the hull; also, in the combination, with this excavator, 30 of means of rotating it and of freeing it from spoil and of dividing the spoil between the several discharging- orifices.

Fig. 1 is a plan of one form of this apparatus and of a portion of a hull on which it and its 35 actuating mechanism may be mounted. Fig. 2 is a side view thereof. Fig. 3 is a longitudinal section through the upper elbow of a suction-pipe leading from the excavator through a bearing in the side of the vessel to a gland 40 connecting it with the suction of a pump. This figure also shows the journal on which rotates the driving-wheel of the chain *r*. Fig. 4 is a perspective of a cylindrical shell with its peripheral buckets and openings used in 45 making a wide cut across the full width of the hull, as shown in Fig. 1. Fig. 5 shows the lower elbows of the suction-pipes leading from the pumps to the interior of the excavator, and between these elbows is shown one form 50 of a bearing or support on which the excavator

may be mounted and around which it may be revolved.

A is a portion of a floating vessel on which the excavating, discharging, and actuating mechanism may be mounted.

B' *B*" are large pumps for relieving the excavator of spoil and for transporting and discharging the same.

C are suction-pipes leading from the pumps to the interior of the excavator.

C' is a discharge-pipe.

D is any suitable bearing for supporting the excavator and serving as a journal or axle on which said excavator may be revolved. It is here shown as a hollow chamber passing 65 through the excavator from elbow to elbow of the suction-pipes, to each of which it is secured. As here shown, it is provided with a longitudinal slot from end to end of the excavator for receiving the spoil therefrom and 70 a central division, *q*, forming two chambers for equally dividing said spoil between the two suction-pipes, as shown in Fig. 17 of the original drawings; but when one suction-pipe only is used this central division must be 75 either omitted or both chambers be provided with separate connections with the suction-pipe. The bearing here shown is made in two equal parts, with outside flanges on their outer ends to secure them to the lower elbows of the 80 suction-pipes and with inside fastenings for securing their inner ends together at *q*. When this mode of mounting the excavator is used it makes a strong connection between the lower ends of the suction-pipes, prevents the admission of too large a percentage of water, and, 85 for a long excavator discharging at both ends, is, perhaps, the best possible form.

E is an excavator. It is here shown as a rotary cylinder or drum, preferably made of steel 90 plates riveted together, and provided with buckets securely fastened over suitable openings in said cylinder or drum, through which the spoil passes from said buckets to the interior of the drum and, in the construction 95 shown, to the interior of the chambers *D* *D*. It is here shown with a double series of six openings and buckets arranged in reversed spirals from the center to the ends, as numbered in Figs. 1, 2, 4, and passing once around 100

- the cylinder, the central bucket being twice as wide as either of the others, so that an equal amount of power is required and an equal amount of work done in each sixth part of a revolution. More than one series may be used to make more than one full cut at each revolution. This excavator may be actuated in any suitable manner. It is here shown as driven by the endless chains r and r' .
10. In this sixth division of the original application I do not claim the combination of a swinging suction-pipe and hollow rotary excavator with an endless driving-chain, the same being claimed in another division of the original application; but
15. What I do claim is—
1. A rotary excavator consisting of a hollow cylinder or drum provided with peripheral excavating devices, openings for admitting spoil from said devices to the interior of said cylinder or drum, and a pipe for receiving and transporting said spoil.
  2. A rotary excavator consisting of a hollow cylinder or drum provided with peripheral excavating devices, openings for admitting spoil from said devices to the interior of said cylinder or drum, and a suction-pipe for receiving and removing said spoil.
  3. A rotary excavator consisting of a hollow cylinder or drum provided with peripheral excavating devices, openings for admitting spoil from said devices to the interior of said cylinder or drum, and an inner hollow cylinder, drum, or shell, having openings for receiving and discharging said spoil.
  4. A rotary excavator consisting of a hollow cylinder or drum provided with peripheral excavating devices, openings for admitting spoil from said devices to the interior of said cylinder or drum, and an inner hollow chamber having openings for receiving and emitting and a pipe for discharging said spoil.
  5. A rotary excavator consisting of a hollow cylinder or drum provided with peripheral excavating devices, openings for admitting spoil from said devices to the interior of said cylinder or drum, and an inner hollow chamber having openings for receiving and emitting and a suction-pipe for removing said spoil.
  6. A rotary excavator consisting of a hollow cylinder or drum provided with peripheral excavating devices spirally arranged around said drum, with openings for admitting spoil from said devices to the interior of said cylinder or drum, and a pipe for receiving and transporting said spoil.
  7. A rotary excavator consisting of a hollow cylinder or drum provided with peripheral excavating devices spirally arranged around said drum, with openings for admitting spoil from said devices to the interior of said cylinder or drum, and a suction-pipe for receiving and removing said spoil.
  8. A rotary excavator consisting of a hollow cylinder or drum provided with peripheral excavating devices spirally arranged around said drum, with openings for admitting spoil from
- said devices to the interior of said cylinder or drum, and an inner hollow cylinder, shell, or drum having openings for receiving and discharging spoil.
9. A rotary excavator consisting of a hollow cylinder or drum provided with peripheral excavating devices spirally arranged around said cylinder or drum, openings for admitting spoil from said devices to the interior of the drum, and an inner hollow chamber having openings for receiving and emitting and a pipe for discharging said spoil.
10. A rotary excavator consisting of a hollow cylinder or drum provided with peripheral excavating devices spirally arranged around said cylinder or drum, openings for admitting spoil from said devices to the interior of the drum, and an inner hollow chamber having openings for receiving and emitting and a pipe for discharging said spoil.
11. A rotary excavator consisting of a hollow cylinder or drum provided with peripheral excavating devices spirally arranged around said cylinder or drum, openings for admitting spoil from said devices to the interior of the drum, and an inner hollow chamber having openings for receiving and emitting and a suction-pipe for withdrawing said spoil.
12. A rotary excavator consisting of a hollow cylinder or drum provided with peripheral excavating devices arranged in reversed spirals from the center toward the ends of said cylinder, openings for admitting spoil from said devices to the interior of said drum, and a pipe for receiving and transporting said spoil.
13. A rotary excavator consisting of a hollow cylinder or drum provided with peripheral excavating devices arranged in reversed spirals from the center toward the ends of said cylinder, openings for admitting spoil from said devices to the interior of said drum, and an inner hollow cylinder or chamber having openings for receiving and conveying said spoil.
14. A rotary excavator consisting of a hollow cylinder or drum provided with peripheral excavating devices arranged in reversed spirals from the center toward the ends of said cylinder, openings for admitting spoil from said devices to the interior of said cylinder, and an inner hollow cylinder or chamber having openings for receiving and emitting and a pipe for discharging said spoil.
15. A rotary excavator consisting of a hollow cylinder or drum provided with peripheral excavating devices arranged in reversed spirals from the center toward the ends of said cylinder or drum, openings for admitting spoil from said devices to the interior of said cylinder or drum, and an inner hollow chamber having openings for receiving and emitting and a suction-pipe for removing said spoil.
16. A rotary excavator consisting of a hollow cylinder or drum provided with peripheral buckets or scoops secured thereto over openings for admitting spoil from said buckets.

or scoops to the interior of said cylinder and a pipe for receiving and conveying the spoil.

17. A rotary excavator consisting of a hollow cylinder or drum provided with peripheral buckets or scoops secured thereto over openings for admitting spoil from said buckets or scoops to the interior of said cylinder and a suction-pipe for receiving and conveying said spoil.

18. A rotary excavator consisting of a hollow cylinder or drum provided with peripheral buckets or scoops secured thereto over openings for admitting spoil from said buckets or scoops to the interior of the cylinder and an inner hollow cylinder, shell, or drum having openings for receiving and discharging spoil.

19. A rotary excavator consisting of a hollow cylinder or drum provided with peripheral buckets or scoops secured over openings for admitting spoil from said buckets or scoops to the interior of said cylinder or drum and an inner hollow chamber having openings for receiving and emitting and a pipe for discharging the spoil.

20. A rotary excavator consisting of a hollow cylinder or drum provided with peripheral buckets or scoops secured over openings for admitting spoil from said buckets or scoops to the interior of said cylinder or drum and an inner hollow chamber having openings for receiving and emitting and a suction-pipe for discharging spoil.

21. A rotary excavator consisting of a hollow cylinder provided with peripheral buckets or scoops arranged in reversed spirals over openings for admitting spoil from said buckets or scoops to the interior of said cylinder and a pipe for receiving and removing the spoil.

22. A rotary excavator consisting of a hollow cylinder or drum provided with peripheral buckets or scoops arranged in reversed spirals over openings for admitting spoil from said buckets or scoops to the interior of said cylinder or drum and a suction-pipe for receiving and removing the spoil.

23. A rotary excavator consisting of a hollow cylinder provided with peripheral buckets arranged in reversed spirals over openings for admitting spoil from said buckets to the interior of said cylinder and an inner hollow cylinder, shell, or drum having openings for receiving and discharging spoil.

24. A rotary excavator consisting of a hollow cylinder or drum provided with peripheral buckets or scoops arranged in reversed spirals over openings for admitting spoil from said buckets or scoops to the interior of said cylinder or drum and an interior hollow cylinder, shell, or drum having openings for receiving and emitting and a pipe for removing the spoil.

25. A rotary excavator consisting of a hollow cylinder or drum provided with peripheral buckets or scoops over openings for admitting spoil from said buckets or scoops to the interior of said cylinder or drum and an inner hollow cylinder, chamber, or drum hav-

ing openings for receiving and emitting and a suction-pipe for removing the spoil.

26. A rotary excavator with inward delivery, in combination with two or more interior chambers, each of said chambers having openings for receiving and discharging spoil.

27. A rotary excavator having peripheral excavating devices with inward delivery, in combination with two or more interior chambers, each of said chambers having openings for receiving and discharging spoil.

28. A rotary excavator with inward delivery through itself into an interior hollow chamber, cylinder, or drum provided with an opening to admit spoil to the interior of said chamber, cylinder, or drum, and a central division to divide the spoil between the openings in said chamber, cylinder, or drum.

29. A hollow cutting, digging, or scooping excavator with inward delivery through itself provided with more than one suction-pipe for removing and a device for dividing the spoil between said pipes.

30. A hollow rotary excavator with inward delivery through itself provided with more than one suction-pipe for removing and a device for dividing the spoil between said pipes.

31. A rotary excavator provided with a series of peripheral excavating-buckets arranged in reversed spirals around the face of said excavator.

32. A rotary excavator with inward delivery through itself, and provided with one or more series of excavating devices, each device constructed and arranged to cut only a part of the breast against which said excavator is working, but unitedly to make at least one full cut across the whole face of the excavation at each revolution, in combination with a conduit for discharging the spoil.

33. A rotary excavator with inward delivery through itself, and provided with one or more series of excavating devices, each device constructed and arranged to cut only a part of the breast against which said excavator is working, but unitedly to make at least one full cut across the whole face of the excavation at each revolution, in combination with a suction-pipe for removing the spoil.

34. A rotary excavator with inward delivery through itself, and provided with one or more series of excavating devices, each device constructed and arranged to cut only a part of the breast against which said excavator is working, but unitedly to make at least one full cut across the whole face of the excavation at each revolution, in combination with a dredge-boat and a device for actuating said excavator.

35. A rotary excavator with inward delivery through itself, and provided with one or more series of excavating-buckets, each bucket constructed and arranged to cut only a part of the breast against which said excavator is working, but unitedly to make at least one full cut across the whole face of the excavation at each revolution, in combination with a dredge-

boat and a device for actuating said excavator.

36. A rotary excavator with inward delivery through itself, and provided with one or more series of excavating-buckets, each bucket constructed and arranged to cut only a part of the breast against which said excavator is working, but unitedly to make at least one full cut across the whole face of the excavation at each revolution, in combination with a conduit for removing the spoil.

37. A rotary excavator with inward delivery through itself, and provided with one or more

series of excavating-buckets, each bucket constructed and arranged to cut only a part of the breast against which said excavator is working, but unitedly to make at least one full cut across the whole face of the excavation at each revolution, in combination with a suction-pipe for removing the spoil.

In witness whereof I hereunto affix my signature in the presence of two witnesses.

A. B. BOWERS.
